[57] CLAIM

The ornamental design for a portable gas lantern, as shown and described.

DESCRIPTION

FIG. 1 is a front elevation view of a portable gas lantern showing a first embodiment of our design having three support feet and a transparent globe;

FIG. 2 is a top left perspective front view of a second embodiment of our design having two support feet and a translucent globe, the second embodiment being identical to the first embodiment except for the third support foot and the globe; and,

FIG. 3 is a top left perspective view of the second embodiment shown in a collapsed condition.

The broken line represents a gas cylinder for illustrative purposes and forms no part of the claimed design.
